United States Patent Office

Des. 210,855

Patented Apr. 23, 1968

210,855

JUG

Victor F. Anderson, 13 W. Mantua Ave., Wenonah, N.J.
08090, and Gerald W. Spotts, 503 Jefferson Drive,
Blackwood, N.J. 08012

Filed Sept. 1, 1966, Ser. No. 3,674

Term of patent 14 years

(Cl. D58—5)

FIG.1

FIG.3

FIG.2

FIG.4

FIG.5

FIG. 1 is a side elevational view of a jug showing our new design;

FIG. 2 is a perspective view;

FIG. 3 is an elevational view looking from the left of FIG. 1;

FIG. 4 is a elevational view on an enlarged scale looking from the right side of FIG. 1; and

FIG. 5 is a top plan view on an enlarged scale.

We claim:

The ornamental design for a jug, as shown.
